Hos. W. Dodge

Edwin G. Moore

Inventor,

David E. Taylor

UNITED STATES PATENT OFFICE.

DAVID E. TAYLOR, OF CHARLTON, MASSACHUSETTS.

CLOTHES-POUNDER.

SPECIFICATION forming part of Letters Patent No. 235,107, dated December 7, 1880.

Application filed September 18, 1880. (No model.)

To all whom it may concern:

Be it known that I, DAVID E. TAYLOR, of the town of Charlton, county of Worcester, and Commonwealth of Massachusetts, have 5 invented certain new and useful Improvements in Clothes-Washers; and I do hereby declare that the following is a full, clear, and exact description of the same, reference being had to the accompanying drawings, forming a part 10 of this specification, and in which—

Figure 1 represents a side view of my improved clothes-washer. Fig. 2 represents a vertical central section on line $x x$, Fig. 1; and Fig. 3 represents a bottom view of the same.

15 To enable those skilled in the art to which my invention belongs to make and use the same, I will proceed to describe it more in detail.

In the drawings, the part marked A represents a case having, in this instance, a convex cover or top, B, and handle-socket C, to receive 20 a handle, D, a section of which handle is shown in Figs. 1 and 2.

Upon the interior of the conical top B is secured 25 a series of braces or stays, a , and to the lower ends of these stays or braces is attached a head-piece, E, made convex on its lower side in this instance; but it may be made of any other desired form.

30 Case A is open at its lower end, and near its lower edge, F, it is provided upon its inner side with a series of loop-springs, G.

Each of the loop-springs G is provided with 35 spring-coils H, one at each of its ends, and the outer ends of the wire, after forming the coils H, are, in this instance, soldered to the inside of case A; but they may be passed through holes formed in the sides of case A, and then soldered or otherwise fastened as may be desired, the only requisite being that the ends 40 of the wire, after the coils H are formed, shall be securely fastened to the case A.

The inwardly-projecting arms b of loop-spring G are bent to form a loop part, c , which 45 passes through a loop-piece, d, projecting from the center head, I, and which center head, I, is made with a hollow, e, into which the loop ends c of the loop-springs G play or work

when said head I is worked up and down in the operation of washing the clothes, as hereinafter described. More or less loop-springs 50 G may be employed, as desired.

By the use of the wire loop-springs G, in combination with the looped head I and case A, as described, there is no danger of tearing 55 or injuring the clothing during the operation of washing, since the clothing slips easily from the surface of the smooth wire, forming the limbs b of the springs G. Then, again, the parts b of the springs G will spring laterally 60 or in any direction, thus conforming automatically to bunches in the clothing or any unusual strain thereof.

The operation is as follows: The wash-tub having been properly filled with clothes and 65 hot soap-suds, the operator takes hold of handle D, which is to be of the desired length, and stamps or forces the case A down into and upon the clothes until it "bottoms," and then raises the washer and repeats this stamping 70 or pounding operation until the clothes are freed from dirt and washed clean.

The head-piece E, which depends from the interior of top B, serves as a stop to prevent the springs being forced too far up into the 75 case, and thereby injured by being set or otherwise; and it also serves as a sucking-head and water-lifter, the water which is lifted being thrown out over its edges, and thus more evenly divided or distributed over the clothes covered 80 by the bottom of case A.

Having described my improvements in clothes-washers, what I claim therein as new and of my invention, and desire to secure by Letters Patent, is—

85

1. The combination, with case A and looped head I, of the wire loop-springs G, substantially as and for the purposes set forth.

2. The combination, with case A, looped head I, and loop-springs G, of head E and 90 braces or stays a , substantially as and for the purposes set forth.

DAVID E. TAYLOR.
